(57) **CLAIM**

The ornamental design for a wearable brim shaper for headwear, as shown and described.

DESCRIPTION

FIG. 1 is a top, right, front perspective view of a wearable brim shaper for headwear, showing my new design; FIG. 2 is a top, right, rear perspective view thereof; FIG. 3 is a top, left, rear perspective view thereof; FIG. 4 is a bottom, right, front perspective view thereof; FIG. 5 is a bottom, right, rear perspective view thereof; FIG. 6 is a bottom, left, rear perspective view thereof; FIG. 7 is a top, rear perspective view thereof; FIG. 8 is a bottom, rear perspective view thereof; FIG. 9 is a front elevational view thereof; FIG. 10 is a rear elevational view thereof; FIG. 11 is a right-side elevational view thereof, a left-side elevational view being a mirror image thereof; FIG. 12 is a top plan view thereof; FIG. 13 is a bottom plan view thereof; and, FIG. 14 is a top, right, front perspective view thereof while in use.

The evenly-broken dashed lines in the views illustrate portions of the wearable brim shaper for headwear that form no part of the claimed design. The unevenly-broken dashed lines in the views define inner peripheral boundaries of the claimed design and form no part of the claimed design. The evenly-broken dashed outline of the headwear in FIG. 14 illustrates the environment of the wearable brim shaper for headwear and forms no part of the claimed design.
